UNITED STATES PATENT OFFICE.

HENRY P. T. VAN KEUREN, OF LANSING, MICHIGAN.

ENGINE.

1,173,132.

Specification of Letters Patent.

Patented Feb. 22, 1916.

Application filed January 23, 1913. Serial No. 743,705.

To all whom it may concern:

Be it known that I, HENRY P. T. VAN KEUREN, a citizen of the United States, residing at Lansing, county of Ingham, State 5 of Michigan, have invented a new and useful Engine, of which the following is a specification.

My invention relates to improvements in internal combustion engines.

10 The object is to provide improved valve control between the engine cylinders and the intake and the exhaust manifolds.

The invention also comprises improvements in cylinder and crank case construction, improvements in cooling methods both by air and water, improvements in the valve oiling system, improvements in magneto drive and in other details of construction.

15 All the foregoing improvements are intended more especially for the four-cycle, multi-cylinder gasoline engines such as are used both in pleasure and commercial vehicles, nautical and aeronautical craft. The larger gas engines of the stationary type or 20 the heavier oil engines of larger craft might, however, advantageously employ some of the principles herein set forth and it is believed that some of them are peculiarly adapted to the types and sizes of engines such as are used in submarine vessels.

25 Referring to the drawings: Figure 1 is a partial side elevation and vertical longitudinal mid-section of a four-cylinder, four-cycle gasoline automobile engine constructed in accordance with my invention. Fig. 2 is a vertical section on line 2—2 of Fig. 1. Fig. 3 is a vertical section on line 3—3 of Fig. 1.

30 Similar numerals refer to similar parts throughout the several views.

In the construction shown in the drawings, which are illustrative, merely by way of example, of a preferred embodiment of my invention, the cylinders 5 are severed by 35 the rotating valve 6. This valve is in the form of a hollow shaft and is provided at intervals both longitudinally and peripherally with recesses 7 forming passageways for the gas and the exhaust at proper intervals in the operation of the engine, as shown and described in my copending application Serial No. 713,998 filed August 8, 1912. Each cylinder 5, whether air or water 40 cooled, is suspended upon the valve member 6 and the said valve member is in turn supported in brackets 11 carrying journals 12.

Brackets 11 are rigidly connected to or made a part of the crank case 13, so that the distance from the axis of the crank to the axis of the rotary valve 6 is fixed. At the 45 lower ends of cylinders 5 there is provided a ground or close fitting sliding joint 14 between each cylinder and the crank case. The object of this joint is to allow a slight relative vertical movement between the cylinders and the crank case.

50 It is obvious that the cylinders are connected to the crank case solely by means of their suspension from the valve 6. Hence compression or explosion pressures tend to move the cylinders vertically upward just as the same pressures force the pistons 15 vertically downward. This reaction is exerted upon the valve and since the valve is rotating constantly, the bearing area of the 55 cylinders upon the valve must necessarily be so proportioned that the unit bearing pressures are within feasible working limits. The valve is in turn restrained by brackets 11 and thus, through the brackets, the cylinder reactions are transmitted to the crank case which carries the crank shaft bearings 9.

60 The object of the suspension of the cylinders in the foregoing manner is two-fold. First, during the compression and expansion strokes when the cylinders are forced upward against the valve, gas-tightness is secured and there can be no leakage of gas around the valve. Second, when the cylinders heat up, more especially in the air cooled types, the expansion of the metal becomes appreciable and since the cylinders are fixed or supported at the valve, changes 65 in length must occur in directions away from the valve and can in no way interfere with the operation of the valve.

65 In the type of engine shown, the cooling is accomplished by means of the natural circulation of water. No pump is used. 70 This system is popularly termed the thermosiphon. Cooling water is supplied to jackets 16 through inlet opening 33, from pipe 34 which is secured to the cylinders by bolts 75. It will be noted that water jackets 16 surround the valve shaft at the top and thereby serve efficiently to cool the same. Water from pipe 34 is also admitted to the interior of valve 6, at the rear end, and flows out at the front and through pipe 10 80 which communicates with pipe 36 extending across the tops of the cylinders and receiv-

ing, through nozzles 42, the water from the tops or jackets 16.

The rotation of the valve and consequent agitation of the water within it will aid the flow. Where the exterior surface of the valve is cooled from the water in jackets 16, it may be found that the interior of valve 6 will require no water cooling, in which case the valve will simply be open at the ends for the access of air.

Referring especially to Fig. 2, gas is supplied from carburetor 27 through passage 39 and intake opening 28 in the cylinder wall to the interior of the cylinder, upon the registering of recess 7 of valve 6 with opening 28 and opening 29 in the cylinder head. Upon the registering at the proper interval in the operation of the engine, of recess 7 with exhaust 30 in the cylinder wall and said opening 29, the exhaust gases are passed from the interior of the cylinder, through passage 40 and into exhaust pipe 31 which is secured by bolts 43 to cylinders 5. The offset 32 to recess 7 of valve 6 and the auxiliary 25 air inlet 8 through the top wall of the cylinder are designed to prevent the trapping of gas within recess 7, all as clearly shown and described in my said copending application. The passages 45 at each of the journals 12 30 and the communicating spirally disposed oil grooves 38 in the outer surface of valve 6, afford means for the lubrication of the valve shaft. Means for reducing the pressure within the crank case, beneath the piston, are indicated by breather 41.

I prefer to drive the valve at half the speed of the crank shaft in the construction shown and by means, for example, of chain 17 and sprockets 18 and 19 secured respectively to crank shaft 44 and valve shaft 6. Since the center to center distance of valve and crank shaft is rather great and means must be employed to take out the slack in chain 17, I utilize a pinion 20 carried in an eccentric bushing 21 and bearing upon the chain, for this purpose. The pinion and its shaft are thus capable of sufficient movement to render the chain taut. The pinion 20 is keyed to shaft 22 and said shaft is connected 50 to the shaft which drives the magneto 24 and the oil pump 25, in such a manner that the eccentric adjustment of the pinion shaft will not interfere with the operation of the magneto shaft.

It should be noted that the cylinders do not necessarily have to be cast singly. They may be cast in pairs or *en-bloc* even, provided the proper journal area is obtained in the supporting brackets. By such casting 60 in pairs or *en-bloc* a considerable reduction in manufacturing cost may be obtained. It will also be noted that the intake and exhaust manifolds may be integral parts of the cylinder casting and that, if desired, the 65 valve shaft may be carried by ball or roller

bearings in brackets 11 with a consequent reduction in friction.

What I claim is:

1. In an engine, the combination of a valve shaft and a cylinder supported thereby and capable of a slight relative movement at an angle thereto. 70

2. In an engine, the combination of a valve shaft, a crank case, and a cylinder between the valve shaft and the crank case, 75 said cylinder having a close ground joint fit with the crank case to permit a slight relative movement between cylinder and crank case.

3. In an engine, the combination of a rotating valve, said valve having a fixed longitudinal axis relatively to the axis of the crank shaft, a cylinder suspended on the valve and a piston within the cylinder, the cylinder being capable of a slight movement 80 in line with the movement of the piston.

4. The combination with a plurality of engine cylinders of supporting means therefor comprising a rotating valve member and brackets between the valve member and the crank case of the engine. 90

5. In an engine, the combination of a rotating valve member, a plurality of cylinders suspended thereon and brackets between the valve member and the crank case 95 of the engine, said brackets forming journal bearings for the valve member at a fixed distance from the crank case.

6. In an engine, the combination of an internally fluid-cooled valve member, a cylinder suspended therefrom and provided with a water jacket adjacent the valve member. 100

7. The combination of a rotary valve member, an engine cylinder having a water jacket cast integral therewith and having a cylinder port and valve seat capable of seating on the rotary valve member, said cylinder suspended upon said valve member. 105

8. The combination of engine cylinders cast integral with water jackets, a rotary valve member journaled in the heads of said cylinders and supporting the same, fixed journal bearings exterior said cylinder castings parallel to and at a fixed distance 110 from the crank shaft bearings.

9. In an engine, the combination of a plurality of cylinders, a rotating valve member, journal bearings therefor between the cylinders, and valve member lubricating 120 means comprising oil passages to the bearings and communicating oil grooves in the outer periphery of the valve member.

10. In an engine, the combination with a plurality of cylinders, of a co-operating valve shaft, jackets about the cylinders, and journal bearings for the valve shaft between the cylinders and outside the jackets. 125

11. In an engine, the combination of a fixed casing, a plurality of cylinders capable 130

- of slight movement therein, a piston operating in each cylinder, a rotatable valve member journaled in the heads of the cylinders for controlling the intake and exhaust of each cylinder and fixed journal bearings for said valve member as means whereby an expansion of a charge in the cylinder causes an efficient engagement of the cylinder member with its seat.
16. 12. In an internal combustion engine, the combination of a cylinder and a piston working therein, a rotary valve journalized in the cylinder and in fixed bearings, the cylinder being suspended upon the valve member and having a close fitting sliding joint with the crank case, as means for transmitting all axial cylinder reactions to said valve.
17. 13. In an internal combustion engine, the combination of a cylinder and a piston operating therein, a rotary valve member journaled in fixed bearings and also in the cylinder, the cylinder being suspended upon the valve member and having a close fitting sliding joint with the crank case, whereby the valve member sustains cylinder reactions.
18. 14. In an internal combustion engine, the combination of a rotary valve-shaft operatively connected to the crank shaft, supporting bearings for the valve-shaft at a fixed distance from the crank shaft, and multiple cylinders suspended from and supported by said valve-shaft.
19. 15. In an internal combustion engine, the combination of a cylinder and a piston operating therein, a rotary valve member and fixed journal bearings therefor, said valve freely journalized in the cylinder, the cylinder being suspended upon the valve member and having a close fitting sliding joint with the crank case, as means whereby a slight movement of the cylinder toward the valve is effected during the period of positive pressures within the cylinder.
20. 16. In an internal combustion engine, the combination of a fixed casing, a plural-
- ity of cylinders movably fitted in the fixed casing, pistons operating in the cylinders, a rotary valve shaft journalized in and supporting the cylinders, said valve shaft having journal supports in the fixed casing as means whereby slight movement of the cylinder toward the valve is effected during the power stroke. 55
21. 17. In an internal combustion engine, the combination of a crank shaft, a rotary cylinder-port-controlling valve operatively connected therewith, valve-carrying bearings parallel with and at a fixed distance 60 from the crank shaft bearings, and multiple cylinders supported by the valve, said valve sustaining all cylinder reactions in line with the cylinder axes for the purpose of allowing the cylinders to seat upon the valve and thus provide a mechanical seal against gas leakage through the cylinder ports and around the valve. 65
22. 18. The combination of a rotary valve member, an engine cylinder suspended on 70 said valve member and having a seat and a seat adapted to operate in such manner that pressure is transmitted from the cylinder to the lower side of the valve member while the upper side is relieved of pressure. 75
23. 19. In an engine employing the thermosiphon method of cooling, the combination of a plurality of cylinders, separate cooling fluid jackets therefor, a hollow rotating 80 valve member, means for supplying cooling fluid to the fluid jackets and to the valve member at one end of said member, and a conductor communicating at separated points with said jackets, and with the opposite end of the valve member. 85
24. 20. In an engine, the combination of an internally fluid cooled valve member and a fluid-cooled cylinder suspended therefrom.
